Primary Examiner — Daniel J Domino(74) *Attorney, Agent, or Firm* — Plumsea Law Group, LLC(57) **CLAIM**

The ornamental design for a display screen or portion thereof with graphical user interface, as shown and described.

DESCRIPTION

The FIGURE is a front view of a display screen or portion thereof with graphical user interface, showing the new design.

The evenly-spaced broken line showing of the display screen, indicia, and other portions of the graphical user interface form no part of the claimed design. The dot-dash lines define the boundary of the claimed design and form no part thereof.
